AUTOMATIC RECLOSED CIRCUIT
BREAKER

James M. Wallace and Albert P. Strom, Pittsburgh, Pa., assignors to Westinghouse Electric Corporation, East Pittsburgh, Pa., a corporation of Pennsylvania

Application July 5, 1951, Serial No. 235,281

19 Claims. (Cl. 200—82)

1

Our invention relates generally to automatic reclosing circuit breakers, and it has reference in particular to circuit breakers of this type wherein a fluid or gas under pressure is used to operate the circuit breaker and extinguish the arc formed during a circuit interrupting operation.

Generally stated, it is an object of our invention to provide in a fluid pressure operated circuit breaker for determining the number of circuit interrupting operations before the breaker is locked open, by means of the amount of pressure fluid in the container supplying the breaker.

Another object of our invention is to provide in a compressed gas operated circuit breaker of the reclosing type, for utilizing time delay means to delay operation of the breaker, and for utilizing means responsive to the pressure of the gas in the circuit breaker tank for rendering the time delay means ineffective for the first one or two operations.

Yet another object of our invention is to provide for operating a reclosing circuit breaker by fluid pressure, and for utilizing the flow of fluid to extinguish any arc which might be drawn.

Another object of our invention is to provide in a compressed gas operated reclosing circuit breaker, for utilizing pressure responsive means for effecting operation of the breaker to lock it in the open position when the pressure in the breaker tank drops to a predetermined operating value.

Still another object of our invention is to provide in a reclosing circuit breaker for utilizing brake means responsive to pressure differentials in the operating means, for delaying reclosing of the breaker after a circuit interrupting operation.

It is also an object of our invention to provide in an automatic reclosing circuit breaker of the compressed gas actuated type, for mounting the breaker and its operating mechanism in a container which has sufficient capacity to store compressed gas for obtaining a predetermined number of breaker operations, and for utilizing pressure responsive means to thereupon effect a locking of the breaker in the open position, if the fault causing operation of the breaker persists.

These and other objects of this invention will become more apparent upon consideration of the following detailed description of a preferred embodiment thereof, when taken in connection with the accompanying drawings, in which:

Figure 1 is an elevational view, broken out in

2

part and partly in section, illustrating a circuit breaker embodying the principal features of the invention;

Fig. 2 is an enlarged cross-sectional view of the upper or interrupter portion of the circuit interrupter shown in Fig. 1;

Fig. 3 is an enlarged sectional view of the lower or actuating portion of the circuit interrupter shown in Fig. 1; and

Fig. 4 is an enlarged sectional view, in part, of the actuating portion, showing the brake in the set position.

Referring to Fig. 1 of the drawings, the reference numeral 10 may denote generally a complete circuit breaker of the compressed gas type embodying the features of the present invention. The circuit breaker may comprise a tank or container 12 for storing compressed gas for operating the breaker and for also enclosing and protecting the breaker mechanism 13. The breaker mechanism 13 may comprise generally fluid actuated means 14 for operating a breaker contact mechanism which may be enclosed in an interrupter structure 16 mounted on the fluid actuated means. Operation of the fluid actuated means may be controlled by a valve mechanism 18 disposed to be controlled by a solenoid operating means 20 including a solenoid coil 21 associated therewith.

The tank 12 may comprise a cylindrical steel side wall structure 22 having flanges 23 and 24 at the ends for securing top and bottom cover plates 25 and 26 thereto by means of bolts or the like (not shown). Electrical connections 35 may be made to the circuit breaker by means of insulating bushings 28 and 29 which may be secured in openings in the top cover plate 25, and conductors 30 and 31 which connect to an intermediate portion of the breaker mechanism 13 and to the operating solenoid 21, respectively.

Compressed gas, such as air or carbon dioxide, or the like, may be supplied to the tank 22 through a needle valve 32 at a rate which is merely sufficient to restore the pressure in the tank after an operation, and is not sufficient to actually supply gas at the rate at which it will be used during a circuit interrupting operation. A solenoid-controlled valve 34 may be provided for venting the tank for reasons which will be explained hereinafter.

Referring particularly to Figs. 2 and 3, it will be seen that the fluid actuated means 14 may comprise a cylindrical tube 36 of insulating material, such as fiber or the like, having a peripheral shoulder 38 intermediate its ends. The tube

36 may be mounted in the bottom cover plate 26 by means of a split ring 39 which engages the tube adjacent the shoulder 38, and an associated clamp ring 40 which may be connected to a ring 42 secured to the cover 26 about an opening 44 through which the lower portion of the tube 36 projects. A gasket 45 may be disposed between the shoulder 38 and the ring 42 for providing a seal therebetween.

A piston 46 may be slidably disposed within the inner bore 47 of the tube 36, having a contact rod 48 secured thereto for actuating one of the breaker contacts. A spring 50 may be disposed in the lower section of the tube 36, being retained therein by a cover 52, for normally biasing the piston 46 to a contact closing position. The piston 46 may be provided with an annular groove 54 disposed to be connected by a passage 56 with the bore 47 of the insulating tube. Ports 57 may be provided in the side walls of the tube 36 at a point slightly below the cover plate 26 for venting the bore 47 when the groove 54 of the piston traverses these ports.

Brake means may be provided in conjunction with the piston 46 for not only stopping the piston when it traverses the ports 57, but also retarding the restoring action of the spring 50 to return the piston to the closed contact position after a circuit interrupting operation. The brake means 60 may comprise a flexible and resilient toroidal brake member 62 of rubber or the like, having a channel-shaped section and loosely disposed in an annular groove 64 so as to provide an annular chamber 65 into which the gas may be admitted through clearances between the brake member 62, the walls of the bore 47, and the sides of the groove 64. An orifice 66 and a needle valve 67 permit release at a controlled rate of the pressure fluid trapped in the chamber to provide a timed braking action when the cylinder is vented. A latch 68 may be provided for engaging the piston 46 through an opening 69 in the tube 36 to lock the breaker in the open position under predetermined operating conditions, as will be explained hereinafter. The latch may be pivotally mounted on the cover plate 26 by means of a pivot 70, and biased into piston engaging relation by means of a spring 72.

The interrupter 16 may comprise a cylindrical insulating body 74 of porcelain or the like having flanged end rings 75 and 76 secured thereto in any suitable manner as may be seen by referring particularly to Fig. 2. The interrupter may be mounted on the insulating tube 36 by means of a split ring 78 which engages the upper end of the insulating tube 36, and a wedge ring 79 to which the end ring 76 may be secured by means of bolts 80. A gasket 82 may be disposed between the insulating tube 36 and the end ring 76 to provide a seal, and a condenser 83 of expanded metal may be disposed in the end ring for cooling gases passing from the interrupter to the fluid actuated means.

Inside the interrupter 16 a movable contact 84 may be mounted on the contact rod 48 for engaging a stationary contact 86. The moving contact 84 may be electrically connected to the end ring 76 by means of a flexible helical shunt 88 for effecting connection to the conductor 30. The stationary contact 86 may be suitably supported in the upper end of the interrupter 16 being, for example, threadedly secured in a boss 90 depending from a valve plate 92 supported on the upper end of the interrupter. The boss 90 may be provided with a plurality of orifices 93 sur-

rounding the stationary contact 86 for permitting the flow of compressed gas therethrough. Immediately surrounding the junction of the stationary contact 86 and the moving contact 84 is an arc chamber 94, which may be provided by securing a cup 95 of insulating material, such as fiber, a refractory, or other suitable arc resistant material, to the dependent boss 90. The cup 95 may be provided with a suitable orifice 97 surrounding the movable contact 84 so as to provide for a blast of compressed gas for extinguishing any arc drawn between the contact members.

The valve mechanism 18 which controls the flow of compressed gas for effecting operation of the breaker may comprise a flexible diaphragm 99 of natural or synthetic rubber or the like, providing the main element. The diaphragm 99 may be mounted on the valve plate 92 which has a central orifice 100 for admitting gas to the interrupter and operating mechanism. The valve plate 92 may be provided with an annular rim 102 surrounding the central orifice 100 so as to define an annular chamber 104 between the valve plate and the diaphragm. A plurality of orifices 105 in the valve plate connect the annular chamber 104 to the main body of compressed gas in the tank 12. The diaphragm 99 may be provided with a pilot valve comprising a movable valve stem 107 having a pilot valve member 110 thereon for closing a pilot orifice 112 in the diaphragm, in its lowermost position, and blocking the valve stem opening 113 in its uppermost position, to seal off the space above the diaphragm 99. A spring 114 normally biases the valve stem 107 to close the pilot orifice 112. The diaphragm 99 may be secured to the valve plate 92 by means of a cap 118 which may be secured to the upper end ring 75 of the interrupter by means of bolts 115.

Operation of the valve stem 107 may be effected by means of a cylindrical core member 116 which may be slidably disposed on the stem and disposed to be actuated by the solenoid operating coil 21. The operating coil 21 may be disposed in a substantially U-shaped frame 117 which may be secured to the cap 118 by means of screws 119 and spacers 120. A sleeve 122 having a flange 123 at its upper end may be threadedly secured to the core 116 at its upper end and slidably disposed on the valve rod 107. Operation of the valve rod may be effected by means of a pin 125 which projects transversely of the valve rod and is disposed to project through slotted openings 127 in the sleeve. Upon a predetermined movement of the sleeve in response to energization of the solenoid coil 21, the pin 125 will be engaged by the bottoms of the slotted openings for actuating the valve stem 107 to open the pilot valve 110 and close the opening 113.

In order to operate the valve stem 107 so as to effect operation of the fluid actuated mechanism 14 for locking the circuit breaker in the open position, pressure responsive means, such as the bellows device 130, may be provided. The bellows device 130 may be provided with a spring 132 disposed to expand the bellows device against the compressive action of compressed gas which surrounds the bellows device within the tank 12. The bellows device may be suitably mounted on a lower portion of the frame 117 of the solenoid coil 21, and provided with an extension 134 for effecting operation of a lever 136 which may be pivotally mounted by means of a pivot 138 on

a substantially U-shaped support 140 mounted on the upper side of the coil supporting frame 117. The lever 136 may be provided with an opening for receiving the upper end of the valve stem 107 which may be provided with lock-nuts 142 to provide for lifting the valve stem when the lever 136 is rotated in a clockwise direction. The extension 134 of the bellows device 130 may be provided with a transverse pin 144 which is disposed to be deflected by means of an L-shaped clip 146 mounted on one side of the support 140 so as to engage the adjacent end of the lever 136 when the bellows expands in response to a predetermined drop in pressure of the gas in the circuit breaker tank 12.

In order to provide for delaying operation of the valve mechanism 18, time delay means 150 may be provided. The time delay means may be of the suction type, comprising a dashpot 151 provided by an annular projection 152 on the cap 118. A suction disc dashpot element 154 may be disposed in the dashpot and secured to the lower end of the core 116 for retarding movement thereof. The dashpot may be filled with a suitable liquid, such as oil or the like, and provided with a cover 156 having sandwiched therein gasket material, such as cork 158, for substantially enclosing the dashpot. In order to provide for an initial one or two relatively fast circuit interrupting operations, means, such as the lever 160, may be provided for initially rendering the time delay means 150 inoperative. The lever 160 may be pivotally mounted on the support 140 by means of a pivot 162 and disposed to engage the flange 123 for lifting the core 116 sufficiently to separate the suction disc 154 from the bottom of the dashpot. This result may be accomplished by having the pin 144 on the bellows extension device 130 engage the lever 160 to rotate it in a counterclockwise direction when the pressure in the circuit breaker tank 12 is sufficiently high, as it will be during the initial one or two operations.

Initially, the pressure in the circuit breaker tank 12 will probably be on the order of 100 p. s. i. Upon the occurrence of an overload, the solenoid coil 21 is sufficiently energized to attract the core 116 upwardly. Because the pressure in the tank 12 is sufficiently high, the bellows device 130 will be compressed sufficiently, so that the pin 144 is engaging the lever 160, and the core 116 will therefore be initially lifted sufficiently that the dashpot suction disc 154 is separated from the bottom of the dashpot, and the dashpot is therefore inoperative to delay movement of the core 116. Accordingly, the core 116 is lifted rapidly, and raises the valve stem 107, thus opening the pilot valve 110 and closing the opening 113. This causes the pressure immediately above the diaphragm 99 to drop to substantially atmospheric pressure which is the pressure in the orifice 100, and the bore 47 of the insulating tube 36. Since full tank pressure is applied to the lower surface of the diaphragm 99 in the annular space 104, the main valve diaphragm 99 lifts, and tank pressure is admitted to the interrupter 16 through the orifice 109. Pressure on the piston 46 forces it downwardly, thus separating the moving contact 84 from the stationary contact 86. Pressure builds up behind the piston 46 and gas flows into the space 65 behind the toroidal brake member 62. As soon as the piston traverses the ports 57, the bore of the insulating tube 36 is vented to the atmosphere, thus permitting gas from the tank 12 to flow rapidly through the arc chamber 94 and extinguish the arc.

As soon as the annular groove 54 of the piston 46 reaches the ports 57, the pressure in the bore 47 is greatly reduced. Gas in the annular chamber 65 behind the brake member 62 thereupon expands, sealing the flanges of the brake member 62 against the sides of the groove 64, as shown in Fig. 4, and forcing the brake member against the inner wall of the tube 36. This not only assists in stopping downward motion of the piston 46, but it also retards the return motion, thus permitting the contacts to remain separated, even though the arc has been extinguished and the pilot valve 110 has been released, whereupon the pressure from the tank builds up in the space on the upper side of the diaphragm 99, being admitted through the clearance around the valve stem 107, causing the diaphragm to immediately seal against the rib 102 to terminate the flow of gas through the interrupter. The gas in the annular chamber 65 leaks out slowly at a rate which may be determined by the setting of the valve screw 67, when the gas pressure in chamber 65 drops so that the starting friction of brake 60 is less than the restoring force of spring 50, the piston will start to move, and once started, will accelerate to close the contacts with snap action.

Should the fault persist, a second interrupting operation will take place similar to that described. In the event that the fault still persists, a third interrupting operation will follow. This operation will be generally similar to the first two, except that operation of the core 116 to lift the pilot valve stem 107 will now be delayed, since the pressure in the circuit breaker tank 12 will have been reduced sufficiently, because of the first two circuit interrupting operations, to permit the bellows device 130 to expand and permit the lever 160 to rotate in a clockwise direction under the gravitational influence of the core 116 so that the suction disc 154 will now be seated against the bottom of the dashpot. This renders the dashpot effective to delay lifting of the pilot valve 110 and thus delay the circuit opening operation. After the suction disc 154 has been separated from the bottom of the dashpot in response to actuation of the core 116, the pilot valve 110 will be opened, and the fluid actuated means will operate to separate the contacts in a manner similar to that described hereinbefore.

In order to lock the breaker open after a predetermined number of circuit interrupting operations, for example, after the fourth operation, the bellows device 130 is disposed to expand sufficiently in response to a reduction in the pressure in the circuit breaker tank 12, so that upon the fourth operation the pin 144 will have reached a position wherein it engages the clip 146 and will be forced sideways by the clip so as to engage the lever 136. Upon opening of the pilot valve 110 by core 116 in response to energization of the solenoid coil 21 for the fourth circuit interrupting operation, the operation will be substantially identical with that hereinbefore described except that the pilot valve 110 will now be held open by the lever 136 being rotated in a clockwise direction about the pivot 133 due to the further reduction in pressure in the tank and the further expansion of the bellows device 130, instead of reclosing immediately upon interruption of the arc. Accordingly, when the piston 46 reaches the position in which the annular groove 54 vents the interior of the insulating tube

36 to the atmosphere and the brake 62 stops the piston 46, gas will continue to flow through the interrupter and fluid actuating mechanism. After the pressure in the annular chamber 65 is reduced sufficiently so as to be equal to the gas 5 pressure of the bore 47, thus releasing the brake 62, the gas pressure remaining in the bore 47 of the insulating tube 36 will still be sufficient to force the piston 46 further down past the ports 57, so that the latch 68 will be disposed in the 10 annular groove 54, thus locking the piston with the contacts in the open position. As the pressure in the tank 12 decreases still further, the bellows device 130 continues to expand, and eventually the pin 144 passes and becomes clear 15 of the clip 145. This releases the lever 136 since the extension 134 will be restored to its normal center-line position, in which position the pin 144 is clear of the lever 136. The pilot valve 110 is thereupon closed by the restoring action of 20 the spring 114, and pressure builds up on the upper side of the diaphragm 99 so as to seal the diaphragm against the annular rib or projection 102 and terminate the flow of compressed gas 25 through the interrupter and fluid actuated means. Pressure in the tank 12 will thereupon be slowly restored to normal from the source through the needle valve 32. The circuit breaker may be 30 reset by operating the latch 68 to release the piston 46, which will then be returned to the contact closing position under the influence of the spring 50.

Tripping of the circuit breaker may also be provided by operating the shunt trip valve device 34 either locally or remotely through suitable control switch means, of any well known type, for venting the tank 12 to atmosphere. The resultant pressure drop in the tank effects 35 operation of the circuit breaker by reason of the bellows device 130 actuating the lever 136 to open the pilot valve 110, whereupon the breaker will be operated to the locked open position in the manner previously described.

From the above description and the accompanying drawings, it will be apparent that we have provided an automatic reclosing circuit breaker in which the compressed gas is both the operating medium and the arc-extinguishing medium. By utilizing a common tank for enclosing the breaker mechanism and containing 50 the compressed gas for operating the breaker, a simple and inexpensive structure is provided. Such a circuit breaker is self-contained, in that all the compressed gas needed for a complete operating cycle is contained within the immediate circuit breaker tank, thus protecting the breaker against failures in the air supply system. By utilizing pressure means for not only controlling the operating time of the breaker but also effecting the lockout operation, a circuit breaker embodying the features of our invention "fails safe," since a loss of compressed gas will cause the breaker to lock open.

Since certain changes may be made in the above described construction, and different embodiments of the invention may be made without departing from the spirit thereof, it is intended that all the matter contained in the above description and shown in the accompanying drawings shall be considered as illustrative, and not in a limiting sense.

We claim as our invention:

1. An automatic reclosing circuit breaker comprising, separable contacts, fluid actuated means for separating said contacts, fluid storage means

containing only sufficient fluid for effecting a predetermined number of closely successive separations of said contacts, means responsive to a predetermined circuit condition for supplying fluid to said actuating means from said storage means, said contact means being biased to close following a contact separation, means responsive to a reduction of pressure of fluid in the storage means to a predetermined value for effecting locking of the contacts in a separated condition after a plurality of closely successive contact separations, and means operable to release said contacts from said condition to reclose the breaker.

2. An automatic reclosing circuit breaker comprising separable contacts, fluid actuated means operable to effect separation of said contacts, fluid storage means containing only sufficient fluid for a limited number of closely successive operations of said fluid actuated means, electro-responsive means operable in response to a predetermined value of current to effect connection of the fluid actuated means to the fluid storage means, time delay means operable to delay separation of said contacts, and pressure means selectively operable to render the time delay means ineffective and effective in accordance with the pressure in said storage means.

3. An automatic reclosing circuit breaker comprising, separable contacts, fluid actuated means for separating said contacts, fluid storage means for storing only sufficient fluid for a limited number of closely successive operations of the fluid actuated means, means responsive to a predetermined condition of a circuit for supplying fluid from said storage means to said fluid actuated means, and means responsive to the pressure of the fluid in the storage means operable when the pressure drops to a predetermined value to effect locking of said contacts in the separated position to effect no more than a predetermined number of closely successive contact separations if said predetermined circuit condition persists.

4. In an automatic reclosing circuit breaker, separable contacts, fluid actuated means for separating said contacts, fluid storage means, means responsive to a predetermined condition of a circuit for connecting said fluid storage means to said fluid actuated means, and pressure actuated means responsive to a drop in pressure of the fluid in said storage means to a predetermined value for effecting a locking operation of the contacts in a separated position.

5. An automatic reclosing circuit breaker comprising, separable contacts, fluid actuated means for separating said contacts, a container for said breaker having fluid under pressure therein for operating said fluid actuating means, valve means operable to supply fluid to said container at a predetermined maximum rate, means responsive to a predetermined condition of a circuit for supplying fluid from said container to said actuating means at a rate in excess of said predetermined maximum rate, means responsive to a drop in pressure of the fluid in the container to a predetermined value for effecting operation of the actuating means for locking said contacts in the separated position when the pressure of the fluid reaches a predetermined minimum value, and means for reducing the pressure in the container to effect a locking operation of said contacts.

6. An automatic reclosing circuit breaker comprising, separable contacts, fluid actuated means operatively connected to at least one of said

contacts for separating said contacts, a container for fluid under pressure housing the contacts and fluid actuated means, fluid actuated valve means operable to supply fluid from the container to said actuating means, and means responsive to a predetermined circuit condition operable to effect operation of said valve means.

7. An automatic reclosing circuit breaker comprising, separable contacts, fluid actuated means operable to effect separation of said contacts, a container for said contacts and fluid means containing fluid under pressure, a diaphragm valve controlling the supply of fluid from said container to said actuating means, a pilot valve in said diaphragm for effecting a flow of fluid to actuate said diaphragm, means responsive to a predetermined circuit condition for operating the pilot valve and thus controlling the supply of fluid to said actuating means for separating said contacts, means operable to close said contacts following a separation, and delay means preventing closing of said contacts for a predetermined time.

8. An automatic reclosing circuit breaker comprising, separable contacts, fluid actuated means operable to separate said contacts, means responsive to a predetermined circuit condition to admit fluid to said fluid actuated means for effecting separation of said contacts, time delay means operable to delay separation of said contacts, pressure means operable to render the time delay means ineffective on a predetermined operation of the fluid actuated means, means biasing said contacts to reclose after separation, and additional means operable only after separation of said contacts to delay reclosing thereof.

9. In an automatic reclosing circuit breaker, relatively movable contacts, an arc chamber for receiving said contacts, fluid actuated means operatively connected with one of said contacts for separating said contacts, said fluid actuated means being connected by a passage with the arc chamber, electroresponsive means responsive to a predetermined circuit condition for supplying fluid under pressure to said arc chamber and fluid actuated means, means operable to reclose said contact, and brake means operable in response to the termination of supply of fluid to the fluid actuated means to maintain the contacts separated for a predetermined time before permitting reclosing.

10. In an automatic reclosing circuit breaker, separable contacts normally biased into engagement so as to reclose automatically following a circuit interrupting operation, fluid actuated means for separating said contacts and extinguishing an arc, a container for fluid under pressure containing said contacts and fluid actuated means, means supplying fluid to said container at a predetermined maximum rate, valve means controlling the admission of fluid from said container to said fluid actuated means at a rate in excess of said maximum in response to a predetermined condition of a circuit through said contacts, and means responsive to a predetermined reduction in pressure in the container controlling said valve means to effect operation of the fluid actuated means to separate said contacts.

11. An automatic reclosing circuit breaker comprising, separable contacts, means normally biasing said contacts together, fluid actuated means for separating said contacts, a fluid container enclosing said contacts and fluid actuated means, said container containing sufficient fluid

under pressure for effecting a plurality of closely successive separations of said contact means, means responsive to a predetermined circuit condition for admitting fluid to the fluid actuated means from the container, means for replenishing the supply of fluid in the container at a rate much slower than it is supplied to the fluid actuated means, and pressure responsive means operable to lock said contacts separated when the pressure in the container reaches a predetermined minimum value.

12. An automatic reclosing circuit breaker comprising, separable contacts, fluid actuated means for separating said contacts, means for biasing said contacts to reclose them, means responsive to a predetermined circuit condition for admitting fluid to said fluid actuated means, brake means operable to retard operation of said fluid actuated means, and means responsive to predetermined pressure conditions for admitting sufficient fluid to said fluid actuated means for effecting further operation of said fluid actuated means for locking said contacts open.

13. An automatic reclosing circuit breaker comprising, separable contacts, fluid actuated means operable to separate said contacts, a container for said contacts and actuating means having sufficient fluid therein under pressure for effecting a plurality of operations of the fluid actuated means to separate said contacts, valve means operable to admit fluid to the container at a predetermined maximum rate, valve means operable to admit fluid from the container to the fluid actuated means at a rate in excess of said maximum, means responsive to a predetermined circuit condition for operating said second mentioned valve means to effect separation of said contacts, means for reclosing said contacts after such an operation, and pressure means responsive to a reduction in pressure in said container to a predetermined value for effecting operation of the valve means to separate the contacts and render the reclosing means ineffective.

14. An automatic reclosing circuit breaker comprising separable contacts, fluid actuated means including a piston movable in a cylinder for separating said contacts, said cylinder having a port disposed to be traversed by said piston for venting the cylinder when the piston has travelled the distance necessary for a normal separation of said contacts, latch means for locking the piston in a more advanced position beyond said port, a fluid container, valve means for admitting fluid to the cylinder from the container, means responsive to an overload for operating the valve means momentarily to admit sufficient fluid to the cylinder to actuate it to uncover said port, means biasing the contacts for reclosing, and means responsive to a reduction of fluid pressure in the container below a predetermined value for operating the valve more than momentarily so as to actuate the piston past said port to render the latch means effective.

15. An automatic reclosing circuit breaker comprising, separable contacts, fluid actuated means for separating said contacts including fluid actuated brake means for limiting operation of the fluid actuated means and delaying reclosing of the contacts, vent means for said fluid actuated means for rendering said brake means effective at a predetermined separation of said contacts, and valve means responsive to a predetermined overload current for admitting fluid under pressure to said fluid actuated means.

16. An automatic reclosing circuit breaker

comprising, separable contacts, fluid actuated means operable to separate said contacts, a container for fluid under pressure, valve means operable to admit fluid from the container to the fluid actuated means, electroresponsive means having a movable part operable in response to an overload to actuate said valve means to admit fluid to the fluid actuated means, time delay means operable to delay movement of said movable part to effect actuation of said valve means, and pressure responsive means operable to render said delay means ineffective so long as the pressure in the container remains above a predetermined value.

17. An automatic reclosing circuit breaker comprising, separable contacts, fluid actuated means operable to separate said contacts, storage means for storing enough fluid under pressure to effect a plurality of operations of the fluid actuated means, valve means operable to admit fluid from the storage means to the fluid actuated means, solenoid means having a movable part operable in response to a predetermined overload current to operate the valve means, time delay means acting on the movable part to delay operation of the valve means, and pressure responsive means having a movable part operable in response to pressures in the storage means of greater than a predetermined amount to move in one direction and render the delay means inoperative, said pressure responsive means being operable in response to pressures in the storage means of less than a predetermined lower amount to move in the other direction to operate the valve means to effect separation of the contacts, said time delay means being effective in response to pressures between said amounts.

18. An automatic reclosing circuit breaker comprising; an arc chamber; a stationary contact and a movable contact disposed to engage in the arc chamber; fluid actuated means including a cylinder connected with the arc chamber and having a movable piston therein connected with the movable contact, said cylinder having a port therein disposed to be traversed by said piston

and latch means for the piston disposed beyond said port; a container for fluid under pressure disposed about the contacts, arc chamber, cylinder and piston; valve means operable to admit fluid from the container to the cylinder through the arc chamber; solenoid means operable in response to an overload current of predetermined value through said contacts to operate said valve means; brake means on said piston having a fluid reservoir for storing fluid to effect operation of the brake means when the piston traverses said vent; means for biasing said contacts to effect engagement upon separation; and means biasing said valve means to terminate the admission of fluid to the fluid actuated means.

19. An automatic reclosing circuit breaker comprising; separable contacts; an arc chamber surrounding the junction of said contacts; fluid actuated means for separating said contacts; means biasing said contacts closed; a container for fluid under pressure, said container being disposed about the arc chamber, contacts and fluid actuated means and disposed to contain sufficient fluid for a predetermined number of operations of the fluid actuated means; valve means for admitting fluid to the fluid actuated means from the container through the arc chamber; means responsive to a predetermined overload condition for operating said valve means; and brake means having a friction element disposed to enclose a pressure chamber subject to fluid pressure from the fluid actuated means for opposing the biasing means and delaying closing of the contacts following a separation.
